UNITED STATES PATENT OFFICE

2,215,236

HOT AIR HEATER

George J. Uckotter, Cincinnati, Ohio

Application February 16, 1938, Serial No. 190,771

1 Claim. (Cl. 126—72)

This invention relates to improvements in hot air heaters of a type utilizing any of the well known types of fuel.

The object of this invention is to provide an ornamental structure of such design that maximum heat may be obtained by the use of a minimum amount of fuel.

More specifically, the invention includes an outer ornamental casing, and an inner casing positioned in spaced relation thereto, the inner casing embodying a multiplicity of horizontally arranged heat tubes directly subjected to the heat from the burner and arranged for the passage of air therethrough, the air thus heated being discharged into the space between the inner and outer chambers for distribution as provided.

Other features will hereinafter appear by reference to the accompanying specification and drawing forming parts of this specification and wherein like characters of reference designate corresponding parts throughout the several views, in which:

Fig. 1 is a side elevation partly in section of an embodiment of the invention.

Fig. 2 is a top plan view with a portion of the ornamental top plate partly cut away.

Fig. 3 is a vertical section on line 2—2 of Fig. 2, and

Fig. 4 is an enlarged view showing the connection between one of the tubes and the inner wall.

The main casing, which may be of any desired size and shape, embodies a base portion 1 cut away at 2 to provide foot portions and a pleasing design at this part of the structure. The walls 3 extend from the base upwardly to form the outer casing and this casing is provided with elongated slots 4 at its two sides, the slots of each side being substantially parallel and extending for the greater part of the width of the heater body and are covered with downwardly deflecting louvers 5 as more clearly shown in Fig. 1.

The front and rear walls are formed with elongated slots 6 positioned substantially in a parallel plane with the elongated slots of the side wall and likewise functioning to permit the entrance of air. One of these elongated slots also permits access through the opening 7 to the burner for lighting the latter in the event that gas or the like is used as fuel. A structure formed of end walls 8, 8', front and rear walls 9, 9', and top plate 10 constitutes an air heating chamber. The four walls comprising this cham-

ber flare downwardly and outwardly at 11 to contact with the outer walls below the horizontal openings 4 and 6 and form with relation thereto deflector plates for directing the movement of air admitted through these openings.

A multiplicity of tubes extend from the front wall to the rear wall in staggered relation and are fastened to these walls at their extremity by the novel type of joint disclosed in Fig. 4. In this figure which is illustrative of any one of the tubes it will be seen that such tubes 12 are provided with reduced extremities 14 thereby providing shoulders 15 which are spaced inwardly of the wall to provided room for the accommodation of the asbestos gasket 16. The inner chamber having no bottom plate is open directly to the heat from the burner 16 shown in dotted line in Fig. 1 and the heat from this burner travels against and through the staggered tubes upwardly and through the flue 16 formed in the top plate 10.

The top plate 10 of the inner heating chamber is spaced a sufficient distance below the upper edges of the outer casing sheets to provide room for the decorative closure plate 11. This plate is formed with a multiplicity of perforations around its edge and inwardly a distance to approximately cover the space between the inner and outer chambers. It will be noted that this cover plate rests upon the top wall of the inner drum and is flanged downwardly at its marginal edges to provide a flange 18 which abuts against the inner face of the outer walls.

In assembling this structure the walls 8, 8' are placed in an aligned perpendicular position, asbestos gaskets 16 are placed on the ends of the pipes 12 and these pipe ends are inserted in the openings in the plates 9, 9'. The walls 8, 8' are then bolted together by elongated bolts 20 and secured together by nuts 21 thus forcing the plates against the asbestos gaskets and the gaskets against the annular shoulders formed at the pipe ends. It will be noted that each of the pipe ends projects beyond the outer face of the walls 8, 8' and into the air passages between the outer and inner walls so that a better deflection of the air currents is provided. With the pipes in position the side walls 8, 8' are then placed in aligned perpendicular position with respect to the walls 9, 9' and sealed and secured along their vertical marginal contacting edges. When so assembled the outwardly flared bottom ends of each of the walls 8, 8' and 9, 9' form a spacing means as well as an air deflector and the extremities of these flared portions are suit-

ably secured to the inner walls of the outer casing immediately below the transverse slots, whereby the air entering the slots is deflected upwardly and across the projecting pipe extremities as shown.

- 5 The foregoing construction provides an assembly in which a maximum amount of air is subjected directly to heat from an adjacent burner in view of the fact that the air is passed from 10 one side of the heater to the other through a multiplicity of staggered tubes. The air is introduced through the outer casing by means of transverse passages situated below the tubes and the movement of the air is facilitated by a curved 15 deflector formed by the outward flaring of the inner heating chamber. The assembly as shown includes any suitable ornamental design on its outer surface and at the top is of pleasing appearance due to the arrangement of perforations 20 in the top plate, the perforations extending around the structure and between the two heating chambers as more clearly shown in Fig. 2. The present device, as previously stated is of such a character that any convenient type of heating 25 element may be utilized, the heating element being confined and within the base of the structure and entirely out of view thus avoiding the disadvantages of the unsightly appearance of burners capable of use in air heaters of this general 30 type.

Obviously the direct contact of the flame on the staggered pipes preheats the air contained in the pipes and sets up a circulation between the

inner and outer casing. The heated air mingles with the in-coming air from the horizontal slots in the outer casing and this heated air escapes through the perforations in the top of the apparatus. Due to the staggered pipe arrangement a maximum amount of heat is absorbed from the heating element and thus the cost of heating is materially reduced.

What I claim as new and desire to secure by Letters Patent is:

In a heater, a main outer vertical casing including a footed base portion and a perforated top, an inner smaller vertical casing having an open bottom and side wall portions which flare downwardly and outwardly and are secured along their horizontal marginal edges to the inner faces of the outer walls of the main casing, a burner within the base portion for heating the inner casing, elongated horizontal slots in the outer casing for directing air streams against the flared portions and thence upwardly between the inner and outer casings, a flue communicating with the inner casing and extending through the top of the outer casing, a plurality of horizontal air heating tubes within the inner casing, the front and rear walls of the inner casing having staggered openings which receive the ends of said tubes, shoulders on said tubes adjacent the ends thereof, gaskets between the shoulders and the inner faces of the corresponding front and rear walls, and elongated bolts which force the front and rear walls against the gaskets.

GEORGE J. UCKOTTER.
